[57] CLAIM

The ornamental design for a carrying case, as shown and described.

DESCRIPTION

FIG. 1 is a top plan view of a carrying case showing my new design;

FIG. 2 is a front elevational view thereof;

FIG. 3 is a side elevational view thereof;

FIG. 4 is a bottom plan view thereof;

FIG. 5 is a rear elevational view thereof;

FIG. 6 is a top plan view of a second embodiment showing my new design;

FIG. 7 is a front elevational view thereof;

FIG. 8 is a side elevational view thereof;

FIG. 9 is a bottom plan view thereof;

FIG. 10 is a rear elevational view thereof;

FIG. 11 is a top plan view of a third embodiment showing my new design;

FIG. 12 is a front elevational view thereof;

FIG. 13 is a side elevational view thereof;

FIG. 14 is a bottom plan view thereof;

FIG. 15 is a rear elevational view thereof; and,

FIG. 16 is a front elevational view of a fourth embodiment showing my new design, the sides, bottom, and rear being substantially the same as FIG. 11.
